POCKET POOL CUE ABRADER

Don L. Turner, Morganfjoreg, Westfield, Wis. 53964

Filed July 1, 1974, Ser. No. 484,626

Term of patent 14 years

Int. Cl. D21—01

U.S. Cl. D34—5 BL

Fig. 1

Fig. 2

Fig. 3

Fig. 4

Fig. 5

Fig. 6

FIG. 1 is a perspective view of a pocket pool cue abrader showing my new design.

FIG. 2 is a top plan view thereof.

FIG. 3 is a side elevational view thereof.

FIG. 4 is a sectional view taken on line 4—4 of FIG. 1.

FIG. 5 is a perspective view of the device open for use.

FIG. 6 is a perspective view as taken from the underside of FIG. 5.

I claim:

The ornamental design for a pocket pool cue abrader, substantially as shown.
